UNITED STATES PATENT OFFICE

121,080

DESIGN FOR A RECEPTACLE FOR COSMETICS

Alfred F. Reilly, North Attleboro, Mass.

Application April 1, 1940, Serial No. 91,397

Term of patent 3½ years

To all whom it may concern:

Be it known that I, Alfred R. Reilly, a citizen of the United States, residing at North Attleboro, county of Bristol, and State of Massachusetts, have invented a new, original, and ornamental Design for a Receptacle for Cosmetics, of which the following is a specification, reference being had to the accompanying drawing, forming a part thereof.

In the accompanying drawing,

The sides not shown of the article illustrated are substantially plain.

The dominant feature of the invention resides in the ornamentation on the cover of the article.

I claim as my invention:

The ornamental design for a receptacle for cosmetics, as shown and described.

ALFRED F. REILLY.
